UNITED STATES PATENT OFFICE

2,656,484

TUNABLE CAVITY

Bruce B. Cork, Beck, Mich., assignor, by mesne assignments, to the United States of America as represented by the Secretary of the Navy.

Application December 27, 1945, Serial No. 637,428.

4 Claims. (Cl. 316—5)

1

This invention relates to a tunable cavity, and more particularly to a tunable resonant cavity adapted for use with a velocity-modulation tube for generating or amplifying high frequency electrical oscillations.

It is an object of this invention to produce a cavity tuning means which operates in a region within the cavity where movement of the tuning means is quite sensitive in varying the resonant frequency of the cavity.

It is another object of this invention to produce a cavity tuning device which is of such a configuration that effective tuning of the cavity is produced without excessive movement of the tuning device.

In accordance with these objects and with other objects which will become apparent, this invention will now be described with reference to the accompanying drawing in which,

Fig. 1 illustrates in cross section an elevation of the cavity taken along line 1—1 of Fig. 2, and

Fig. 2 illustrates in cross section a plan of the cavity taken along line 2—2 of Fig. 1.

Referring to the drawing, the cavity is seen to be constructed in the form of a hollow toroid 10, having annular conducting walls 11 and 12 closed by a conducting peripheral wall 13. An indentation in wall 11 is formed by circular wall 14 and annular wall 15.

This indentation provides a means for holding a tube, exemplified in this embodiment as a reflex velocity-modulation tube 20, in the hole of toroid 10. Tube 20 is a conventional type of velocity-modulation tube. The tube comprises an electron gun 21, resonator grids 22 and 23, and a reflector electrode 24. Grids 23 and 22 are connected electrically to annular external terminals 24 and 25, respectively, which are held in contacting relation with walls 15 and 12, respectively, of cavity 10, by means of ring holders 30 and 31. Holders 30 and 31 bear against terminals 24 and 25, respectively, and are held to walls 15 and 12, respectively, by suitable securing means such as screws or bolts.

The structure described thus far will be recognized as a conventional reflex velocity-modulation oscillator comprising principally velocity-modulation tube 20 and specially-shaped resonator cavity 10.

The instant invention concerns tuning means for cavity 10, in the form of a pair of conductive segments 40 and 41, which, placed together, form a ring having an inner diameter slightly larger than the hole in the center of the toroid. This will be clearly seen in Fig. 2 where the two seg-

2

ments 40 and 41 of the ring are shown touching at 42 and 43.

The electrical effect of ring segments 40 and 41 is that of capacity loading for cavity 10 near the center thereof, where the effect is much more pronounced than elsewhere in the cavity. Ring segments 40 and 41 may be moved radially by means of the attached non-conductive rods 44 and 45, respectively. In use, it is preferable to move the ring segments 40 and 41 simultaneously; and for this purpose some form of ganged tuning means for rods 44 and 45 may be provided.

Output from the oscillator is derived thru output loop 50 feeding a coaxial transmission line 51.

In operation, the cavity may be resonated over a continuously variable frequency band by movement of ring segments 40 and 41 between the position shown in solid lines and the position 46—47, shown in dotted lines. Over the region illustrated, the resonant frequency of the cavity has been found to be very sensitive to the position of ring segments 40 and 41. This sensitivity is believed to be due to a combination of two effects. The first effect concerns the sensitivity of the cavity to capacity loading near its center, as opposed to outer regions of the cavity. The second effect concerns the decrease in capacity between conductive ring segments 40—41 and the opposite wall, encountered at the abrupt points 52 and 53, where the thickness of the cavity suddenly increases. Therefore, outward movement of ring segments 40—41 not only results in decreased capacitive action, but also removes the capacity from the center of the toroid where its effect is most pronounced.

From the above description, it will be seen that there has been described a tuning means for a cavity, capable of controlling the resonant frequency of the cavity over a continuous and wide range of frequencies without excessive movement of the tuning device.

Although I have shown and described certain specific embodiments of the invention, I am fully aware of the many modifications possible thereof without deviating from the scope of the present invention.

What is claimed is:

1. A cavity resonator formed by walls made of conductive material, there being an opening in said walls, a thin conductive ring disposed within said cavity resonator and occupying only a fractional portion of the distance between opposing

wall surfaces in the vicinity of said opening, said conductive ring being split into segments, said segments when brought together having an inner boundary slightly larger than said opening, each segment of said conductive ring being movable to tune said cavity resonator, and an output loop disposed within said cavity resonator remote from said opening.

2. A cavity resonator formed by walls made of conductive material, there being an opening centrally disposed in said walls, a thin conductive ring circumscribing said opening and disposed upon one wall of said cavity resonator, said conductive ring occupying only a fractional portion of the distance between opposing wall surfaces in the vicinity of said opening, said conductive ring being split into segments, said segments when brought together having an inner boundary slightly larger than said opening, each segment being radially movable to tune said cavity resonator, and an output loop disposed within said cavity resonator remote from said opening.

3. A cavity resonator for use with an electron beam device comprising walls made of a conductive material forming a cavity, there being an opening in said walls through which said electron beam device is to pass, tuning means comprising moveable segments mounted within said cavity and extending about said opening, said tuning means when brought together having an inner boundary slightly larger than said opening, said segments having a height which is sufficiently small so that the enclosed volume of said cavity

is not appreciably affected by said segments, means connected to said segments for moving same relative to each other.

4. A cavity resonator for use with an electron beam device comprising walls made of a conductive material forming a cavity, there being an opening in said walls through which said electron beam device is to pass, the distance between opposing wall surfaces in the vicinity of said opening being substantially less than the distance between opposing wall surfaces from said opening, tuning means comprising radially moveable segments mounted within said cavity and extending about said opening in the vicinity thereof, said tuning means when brought together having an inner boundary slightly larger than said opening, said segments having a height which is sufficiently small so that the enclosed volume of said cavity is not appreciably affected by said segments, means connected to said segments for moving same relative to each other.
